UNITED STATES PATENT OFFICE

WILBUR B. DRIVER, OF EAST ORANGE, NEW JERSEY

RADIOTUBE

Application filed June 27, 1929. Serial No. 374,049.

This invention relates to radio tubes.

It has been customary to make the plate material of radio tubes of solid sheet metal. A more effective operating tube can be secured by using a plate material having openings therein. Plain round wire mesh has been used but such material has developed some unfavorable characteristics due to the fact that the wire mesh is composed of round wires and due to the fact of the protruding ends of the wires. A further difficulty is found in the removal of foreign matter from the wire mesh which has a tendency to collect in the interstices of the crossed wires and which has proved detrimental in correct evacuation of the tube during manufacture and subsequently in effecting the proper functioning of the tube. One of the reasons for the utilization of a wire mesh plate material 20 is the increased heat radiating qualities over a solid plate.

One of the objects of this invention is to provide a radio tube with a form of plate that will have the combined good qualities 25 of a solid metal plate and a round wire mesh without any of the bad qualities of either of the two materials.

Still another object of this invention is to provide a plate material for radio tubes having a plane surface of uniform thickness and with a relatively large number of openings 30 therein.

Still another object of this invention is to provide a plate material wherein the ratio of 35 the openings to the solid material can be readily varied or controlled to obtain the best characteristics for a particular tube.

A further object of this invention is to provide a radio plate material having a plurality 40 of openings therein and wherein the metallic surfaces are smooth and form plane surfaces having no interstices of crossed wires to collect dirt, which latter hinders the proper evacuation of the tube during manufacture.

45 A further object of this invention is to provide a smooth solid edge for the plate material formed from the wire mesh and integral therewith to obviate the bad characteristics of the protruding ends of a wire mesh.

50 Referring to the drawings:

Figure 1 is a plan view of the plate material.

Figure 2 is an end view of Figure 1.

Figure 3 is an end view of the material without a selvedge edge.

55 Figure 4 is a view of a radio tube embodying my invention.

Figure 5 is a sectional view along the line 5, 5, looking in the direction of the arrows.

In carrying out my invention I propose to 60 make the plate 1 from two pieces of mesh material 2 and to weld the free ends to supporting conductors 3. An alternative method is to make the plate 1 of a single piece of mesh 2 and to weld same together and to the electrical conductors 3. In a previous application Serial No. 370,721 filed June 8, 1929, I have 65 more fully described the method of making and the form of mesh which I have found to be advantageous as a plate material. Mesh 70

2 is a wire mesh which has been rolled under pressure to form the two surfaces of the mesh into plane surfaces and the wires into substantially the same plane. The mesh 2 preferably has formed around its edges a solid 75 selvedge of the same thickness and in the same plane as the mesh. This selvedge is made integral with the mesh and from the wires of the mesh itself.

Mesh 2 having a smooth metallic surface has no interstices between 80 crossed wires to collect dirt and can be readily cleaned and kept cleaned in the process of manufacture. The solid selvedge edge has the same effect as an edge of a solid piece of plate material, that is, it does not have the 85 protruding wires of the ordinary round mesh having no such selvedge and therefore will function more perfectly.

As the size of the openings may be controlled in the mesh by the degree of rolling, 90 the mesh may be made to fit the exact characteristics of any particular tube.

It will thus be seen that I have invented a radio tube having a plate material adaptable to the characteristics of different tubes 95 and which will embody the good qualities of both a solid plate material and a round wire mesh without the disadvantages of both.

What I claim is:

1. A plate for a radio vacuum tube of wire 100

mesh, the metallic surfaces of said mesh being plane surfaces, the free edges of said wire mesh having a substantially solid metallic selvedge integral with the wires and in the same plane as the wire mesh.

- 5   2. A plate for a radio vacuum tube of wire mesh, the wires of said mesh in substantially the same plane, the surfaces of said mesh being smooth, the free edges of said wire mesh
10 having a substantially solid metallic selvedge integral with the wires in the same plane as the wire mesh.

15   Signed at Newark in the county of Essex and State of New Jersey this 18th day of May, A. D. 1929.
